UNITED STATES PATENT OFFICE

104,246

DESIGN FOR A SPRAY APPARATUS FOR PREVENTING OFFSET IN PRINTING

Alessandro Della Chiesa, Douglaston, N. Y., and
Louis P. Froehlich, East Rutherford, N. J.

Application February 4, 1937, Serial No. 67,448

Term of patent 14 years

To all whom it may concern:

Be it known that we, Alessandro Della Chiesa and Louis P. Froehlich, both citizens of the United States, and residents of Douglaston, county of Queens, and State of New York, and East Rutherford, county of Bergen, and State of New Jersey, respectively, have invented a new, original, and ornamental Design for a Spray Apparatus for Preventing Offset in Printing, of which the following is a specification, reference being had to the accompanying drawing, forming part thereof.

Figure 1 is a perspective view of a spray apparatus for preventing offset in printing, showing my new design,

Figure 2 is an end elevational view thereof, and

Figure 3 is a top plan view of the same.

We claim:

The ornamental design for a spray apparatus for preventing offset in printing, as shown.

ALESSANDRO DELLA CHIESA,
LOUIS P. FROEHLICH.
